ADOLPH REIMHERR, OF BRIDGEPORT, CONNECTICUT, ASSIGNOR TO WHITING MANUFACTURING COMPANY, OF NEW YORK, N. Y., A CORPORATION OF NEW YORK.

DESIGN FOR A HANDLE FOR A SPOON, FORK, OR SIMILAR ARTICLE.

54,452.

Specification for Design.

Patented Feb. 10, 1920.

Application filed March 7, 1919. Serial No. 281,312. Term of patent 14 years.

To all whom it may concern:

Be it known that I, ADOLPH REIMHERR, a citizen of the United States, residing at Bridgeport, in the county of Fairfield and State of Connecticut, have invented a new, original, and ornamental Design for a Handle for a Spoon, Fork, or Similar Article, of which the following is a specification, reference being had to the accompanying drawing, in which—

Figure 1 is a view of the obverse face of a

spoon embodying my new design; Fig. 2 is a corresponding view of the reverse face; Fig. 3 is a view of the tip of the handle, similar to Fig. 1 but on a larger scale, and Fig. 4 is a transverse section through such tip, taken on the line 4—4 in Fig. 3.

I claim:—

The ornamental design for a handle for a spoon, fork, or similar article, as shown.

ADOLPH REIMHERR.
